ROBERT J. NORTHAM AND WALTER E. SANDHAM, OF LOS ANGELES, CALIFORNIA,
ASSIGNORS TO NORTHAM AUTO PRESSURE GAUGE CO., OF LOS ANGELES, CALI-
FORNIA, A CORPORATION OF CALIFORNIA.

EXPLOSION-ENGINE-STARTING MECHANISM.

984,840.

Specification of Letters Patent. Patented Feb. 21, 1911.

Application filed October 19, 1910. Serial No. 587,898.

To all whom it may concern:

Be it known that we, ROBERT J. NORTHAM and WALTER E. SANDHAM, both citizens of the United States, residing at the city of 5 Los Angeles, county of Los Angeles, State of California, have invented new and useful Improvements in Explosion-Engine-Starting Mechanism, of which the following is a specification.

10 Our invention relates to apparatus for cranking engines and is primarily designed for automobiles; and the object thereof is to provide a simple and inexpensive mechanism that will prevent injury to the person 15 cranking the engine, should the same back-kick when being started.

We accomplish this object by the mechanism described herein and illustrated in the accompanying drawings forming a part here- 20 of in which:

Figure 1 is the front view of a part of an automobile equipped with our improved starting mechanism. Fig. 2 is a side elevation partly in section, and partly broken 25 away, of our starting mechanism in place ready for operation. Fig. 3 is a front elevation of the cranking mechanism illustrated in Fig. 2. Fig 4 is a top plan view of the parts shown in Fig. 3 with the handle omitted. Fig. 5 is a side elevation of the 30 upper portion of our cranking mechanism in its inoperative position.

In the drawings 10 is the cranking shaft which is provided with a clutch on its inner 35 end which engages with a clutch on the engine shaft, in the usual well known manner when it is desired to crank the engine.

11 represents a portion of the auto frame in which the crank shaft is revolvably and 40 slidably mounted. Upon the outer end of the cranking shaft is revolvably mounted, cranking lever 12 having at its outer end an operating handle 13. Adjacent to lever 12 and rigidly mounted upon the cranking 45 shaft is locking lever 14. Slidably mounted upon the cranking lever is a sleeve 15 which is provided upon its inner end with an upwardly extending lug 16. In the inner end of the sleeve is a pocket or recess 17 into which the end of locking lever 14 is received when it is desired to crank the engine. In the outer 50 end of the sleeve is a socket 18 which houses a spring 19. One end of the spring rests against the sleeve and the other end rests

against a pin 20 which is secured by a screw 55 21 to lever 12. A pin 22 is also secured to lever 12 and limits the inward movement of sleeve 15 upon lever 12. Normally spring 19 holds the sleeve spring pressed against pin 22, with the locking lever locked thereby in recess 17. In the outer end of lug 16 is mounted a dog 23 which when the cranking shaft is in position to crank the engine engages teeth 25 of the ratchet wheel 26, 60 which wheel is rigidly secured upon a boss 27 upon that part of the frame in which the cranking shaft is mounted. Dog 23 has an oscillating movement in its bearings and the outer end is held spring pressed outwardly by means of spring 28 which is 65 partly housed in a socket 29 in the outer end of lug 16.

The operation of our device is as follows: The operator pushes the cranking shaft inwardly and turns the same to the right in 70 the usual well known manner. When moving in this direction dog 21 rides over the teeth. Should the engine back-kick the cranking shaft would be turned in the reverse direction, when the dog would catch 75 in the teeth of the ratchet wheel, thereby forcing sleeve 15 downwardly and releasing the outer end of lever 14 from engagement with the sleeve. As soon as lever 14 is released from the sleeve it is unlocked from the 80 cranking lever and the cranking shaft and lever 14 can revolve independently of the cranking shaft until the motion of the cranking shaft ceases. In the meantime the cranking lever remains in the hands of the operator 85 without movement. The operator then brings the parts to the position in Fig. 2 when he again proceeds to crank the engine.

By this construction a simple and inexpensive mechanism is provided for cranking 90 the engine which automatically releases itself upon the back-kick of the engine. A strap 30 may be provided to hold the cranking lever when not in use.

Having described our invention what we 100 claim is:

1. A starting mechanism for explosion engine comprising a cranking shaft; two levers mounted upon the outer end of the cranking shaft, one of said levers being 105 rigidly secured to the cranking shaft and the other being revolvably mounted upon the cranking shaft; means to lock said levers

- together to turn the cranking shaft in a direction to start the engine; and means for unlocking said locking means when the cranking shaft is turned in the opposite direction.
2. A starting mechanism for explosion engines comprising a crank shaft; a cranking lever revolubly mounted upon the outer end of said cranking shaft; a locking lever rigidly mounted upon said cranking shaft adjacent to the cranking lever, said locking lever being shorter than the cranking lever; a spring pressed sleeve slidably mounted upon the cranking lever, said sleeve having a recess in the top thereof into which the end of the locking lever is received when the levers are locked together; a non-revoluble ratchet wheel surrounding said cranking
- 10
- 15

shaft; a spring pressed dog mounted upon said sleeve adapted to engage the teeth of the ratchet wheel and to depress the sleeve and carry it out of engagement with locking lever upon the rotation of the crank shaft in one direction and to slide over the teeth upon the rotation of the cranking shaft in the reverse direction; and means to limit the movement of said sleeve.

In witness that we claim the foregoing we have hereunto subscribed our names this 4th day of October, 1910.

ROBERT J. NORTHAM.
WALTER E. SANDHAM.
